(57) **CLAIM**

The ornamental design for a silicone necklace holder for a rollerball bottle, substantially as shown and described.

DESCRIPTION

FIG. 1 is a front perspective view of a silicone necklace holder for a rollerball bottle showing the new design; FIG. 2 is a front elevation view thereof; FIG. 3 is a rear elevation view thereof; FIG. 4 is a left side view thereof; FIG. 5 is right side view thereof; FIG. 6 is a top plan view thereof; FIG. 7 is a bottom plan view thereof; and, FIG. 8 is an illustrative bottom perspective view showing the silicone necklace holder attached to a necklace and a rollerball bottle.

The broken lines in the drawings are for purposes of illustrating environmental subject matter that form no part of the claimed design.
